UNITED STATES PATENT OFFICE

GEORGE A. VEETMEIER, OF MILWAUKEE, WISCONSIN

CURTAIN OR DRAPE ROD ATTACHMENT

Application filed November 25, 1930. Serial No. 498,169.

This invention relates generally to window drapes and curtains and has for its primary object to provide, in a manner as hereinafter set forth, an attachment for the supporting rods or devices of the drapes or curtains which is ornamental and highly attractive in appearance and which further includes means for expeditiously mounting said attachments in position or removing the same when it is so desired.

Another important object of the invention is to provide ornamental attachments for window drapes and curtain rods which are adapted to be mounted on the angular corner portions of the rods and on the straight intermediate portions of the rods.

Other objects of the invention are to provide an ornamental attachment for window drape and curtain rods of the character described which will be simple in construction, strong, durable, efficient and which may be manufactured at low cost.

All of the foregoing and still further objects and advantages of the invention may become apparent from a study of the following specification, taken in connection with the accompanying drawings wherein like characters of reference designate corresponding parts throughout the several views, and wherein:—

Figure 1 is a perspective view showing the ornamental attachments constituting this invention mounted in position on a window drape supporting rod.

Figure 2 is a view in top plan showing the ornamental attachments mounted in position on a window drape supporting rod.

Figure 3 is a view in rear elevation of the ornamental attachment which is mounted on the straight intermediate portion of the rod.

Figure 4 is a view in elevation showing one of the ornamental attachments which are mounted on the end portions of the rod.

Figure 5 is a vertical sectional view taken substantially on the line 5—5 of Figure 3 showing the intermediate attachment mounted in position on the rod, said rod being also shown in cross section.

Figure 6 is a sectional view taken vertically through one of the angular attachments

which are mounted on the corner portions of the rod.

Referring to the drawings in detail, it will be seen that the reference numeral 1 designates a conventional window frame upon the upper portion of which are mounted the outwardly extending substantially U-shaped curtain and drape supporting rods 2 and 3, respectively. The rods 2 and 3 are of conventional construction and a curtain 4 is supported on the rod 2 and drapes 5 are suspended from the end portions of the rods 3 in the usual manner.

The reference numeral 6 designates a plate which is formed of any suitable material, preferably metal which is attractively ornamented by stamping or embossing the same or by any other suitable means such as painting, the plate 6 being of ornamental configuration and being adapted for disposition against intermediate portions of either of the rods 2 and 3. Arms or clips 7 are formed integrally at spaced points on the upper edge of the plate 6 and said arms or clips extend downwardly in the rear of the plate 6 for engagement over the curtain or drape rod in a manner to support the plate 6 detachably thereon as shown, the plate 6 is formed with a marginal flange 6' which extends inwardly and the ends of the clips 7 are connected to this flange so that the top part of the flange rests upon the rod 2 or 3 and this helps the clips to support the plates from the rod. Any desired number of the arms or clips 7 may be provided on the plate 6 and said arms or clips may be spaced as desired.

For disposition on the corner portions of the rods 2 and 3, angular plates 8 are provided, said plates being of the same type and having the same characteristics of the intermediate plate 6. Supporting arms or clips 9 similar to the arms or clips 7 are provided on the end portions of the angular plates 8 for engagement over the rods 2 and 3.

It will thus be seen that a highly ornamental and attractive attachment for drape and curtain rods has been provided which will lend a finished appearance to the drapes and the curtains and which may be expeditiously mounted in position or removed. It is

2
understood, of course, that the attachments may be mounted either on the drape rod or on the curtain rod or on both.

It is believed that the many advantages of a curtain and drape rod attachment in accordance with this invention will be readily understood, and although the preferred embodiment of the invention is as illustrated and described, it is to be understood that changes in the details of construction may be had which will fall within the scope of the invention as claimed.

What is claimed is:—

15 An ornamental plate for curtain or drape rods, having a straight upper edge formed with an inwardly extending flange for resting on the top part of the rod and a number of clips for attaching the plate to the rod, each clip having a long vertical leg and a 20 short horizontal leg, the end of the short leg being attached to the free edge of the flange.

In testimony whereof I affix my signature.

GEORGE A. VEETMEIER.
